MOUNTING ARRANGEMENT FOR ELECTRON
DISCHARGE DEVICES

Christopher Henry Foulkes, London, England, assignor, by mesne assignments, to International Standard Electric Corporation, New York, N. Y., a corporation of Delaware

Application April 13, 1945, Serial No. 588,211
In Great Britain April 7, 1943

Section 1, Public Law 690, August 8, 1946
Patent expires April 7, 1963

4 Claims. (Cl. 250—27.5)

1

The present invention relates to mounting arrangements for electron discharge devices and in particular for those devices in which an electron beam is generated and focussed by a magnetic field.

In electron velocity modulation tubes in which resonators are excited by firing a beam of electrons therethrough (for example in a device of the kind disclosed in Patent Specification 2,320,860), it is often desirable to focus the beam by applying a magnetic field of suitable strength in which the lines of force are substantially parallel to the beam. This is usually done by mounting the tube or device between the poles of a magnet. These tubes are often manufactured in a form not unlike an ordinary thermionic valve so that replacements can be easily made. It has, however, been found difficult to ensure that the necessary coincidence between the directions of the electron beam and of the magnetic field is maintained after a replacement, since this requires the use of appropriate test apparatus or indicators operated by trained personnel, which may be impracticable when replacements have to be made in apparatus operated in the field away from a factory or laboratory.

The present invention is directed towards the remedying of this difficulty by providing the tubes which have to be replaced with mounting means which is adjusted before leaving the factory or laboratory, so that replacements may be made in the field without the use of special apparatus, or by skilled operators.

According to the invention, there is provided an adjustable clamp for holding an electron discharge tube in the field of a magnet, comprising means for mounting the clamp on the poles of the magnet so that when the tube is in the clamp, the axis of the tube is at right angles to the magnetic lines of force, the clamp being adapted to allow the tube to be rotated about the said axis.

The invention may also comprise an electron discharge tube of the kind in which an electron stream is operated in the field of a magnet, provided with a clamp for holding the tube between the poles of the magnet in such a manner as to allow the tube to be rotated about an axis for the purpose of adjusting the orientation of the electron stream in the field, the clamp being adapted to be mounted on the said poles.

This invention may further comprise an electron discharge tube having means for directing an electron beam transversely to the axis of a co-axial line resonator, provided with a clamp adapted for holding the tube while allowing it

2

to be rotated about the said axis in the field of a magnet, so that the said beam may be set parallel to the said field, means being provided for mounting the clamp on the poles of the magnet.

5 The invention will be described with reference to the accompanying drawing, in which Fig. 1 shows a perspective view of an adjustable mounting clamp, and Fig. 2 shows a perspective view of an electron discharge tube mounted between the poles of a magnet by means of the clamp shown in Fig. 1.

The electron discharge tube 1 shown in Fig. 2 comprises a cylindrical envelope 2 mounted on a base 3 which carries terminal pins 4 adapted to engage a socket arrangement 5 in the manner common in valve practice. The tube 1 may contain a co-axial line resonator arranged co-axially with the envelope 2 and excited by a transverse electron beam in the manner described in the above mentioned specification.

15 The focussing magnetic field is produced by a magnet 10, and the tube 1 is mounted between the poles of the magnet by means of the clamp 11, which is adapted to rest on the poles in the manner indicated in Fig. 2 so that the tube 1 is in the desired position.

25 The clamp 11 comprises two similar halves 12, 13 fixed together by screws above and below, one of which is shown at 14. A cylindrical channel 30 15 is thus formed, into which the envelope 2 may be inserted, the tube being firmly gripped when the screws 14 are tightened. Each half of the clamp is provided with a pair of side lugs 16 adapted to fit squarely on the pole pieces of the magnet 10.

35 The clamp 11 may be a pressing of any non-magnetic metal such as brass, or it may be a moulding in a synthetic resin, or the like. It may be fixed to the magnet in any convenient way, 40 such as by springing inwards the side faces 17 of the lugs, or by screws into the pole pieces arranged in any suitable way. One convenient and simple method is to fix a thin plate 20 of magnetic material to the underside 18 of each pair 45 of lugs 16, so that the clamp is held down by magnetic force. If desired, the side faces 17 may in addition be sprung inwards, as already mentioned.

45 In order to prevent crushing of the envelope 2 when the clamp is being tightened, one or more layers of asbestos paper or other appropriate padding material is preferably placed round the envelope at 19 underneath the clamp.

50 Before being sent out, each tube is provided 55 with a clamp 11. The clamp is loosened suffi-

ciently and placed with the tube on a magnet 10 which is a duplicate of the one in the apparatus in which the tube is to be used. The tube is then rotated until the electron beam is brought parallel to the magnetic field as indicated by appropriate test instruments connected to the tube. The clamp is then tightened, and the tube with clamp attached is then sent out. This ensures that when it is mounted in the apparatus on the magnet 10 as explained, the electron beam will be in the right direction, and thus the replacement can be made by any not specially skilled operator.

Although a co-axial line resonator has been cited as an example of a tube to which the invention is applicable, it is not restricted to this particular type. Any electron discharge tube requiring to be oriented with respect to a magnetic field could be similarly equipped, provided it can be conveniently designed with a cylindrical envelope. For example, the invention could be adapted to devices of the magnetron type.

What is claimed is:

1. An adjustable clamp for holding an electron discharge tube in the field of a magnet, comprising similar halves fastened together to form a cylindrical channel for embracing externally the envelope of the tube, the said halves being pro-

vided with means for mounting the clamp on the poles of the magnet.

2. An adjustable clamp according to claim 1, in which each of the said halves is provided with a pair of side lugs shaped to conform with one of the poles of the magnet.

3. An adjustable clamp according to claim 1, in which the said halves are of non-magnetic material.

10 4. An adjustable clamp according to claim 1, in which each of the said halves is principally of non-magnetic material and is provided with a pair of side lugs shaped to conform with one of the poles of the magnet, a plate of magnetic material being fixed to each pair of said lugs so as to come into contact with the corresponding pole of the magnet for holding the clamp thereon by magnetic force.
